[57] CLAIM

The ornamental design for a corner connector for
knock-down furniture, as shown and described.

DESCRIPTION

FIG. 1 is a perspective view of a corner connector
showing an installing plug in place;

FIG. 2 is a top plan view thereof;

FIG. 3 is a bottom plan view showing bottom of an
installing plug and a mini-pipe fastener in place;

FIG. 4 is a front view thereof;

FIG. 5 is a right view thereof;

FIG. 6 is a left view thereof;

FIG. 7 is a back view thereof.
